UNITED STATES PATENT OFFICE.

WILLIAM H. BILLINGSLEY, OF FLORENCE, ALABAMA.

DESIGN FOR AN ORNAMENT FOR AUTOMOBILE RADIATOR CAPS.

Application filed January 2, 1925. Serial No. 11,856. Term of patent 7 years.

To all whom it may concern:

Be it known that I, WILLIAM H. BILLINGSLEY, a citizen of the United States of America, residing at Florence, in the county of Lauderdale and State of Alabama, have invented a new, original, and ornamental Design for Ornament for Automobile Radiator Caps, of which the following is a specification, reference being had to the ac-

companying drawings, forming a part hereof.

The figure is a perspective view showing my new design for ornament for automobile radiator caps.

I claim:

The ornamental design for an ornament for automobile radiator caps as shown.

WILLIAM H. BILLINGSLEY.
